METHOD OF PREPARING WELLS FOR PRODUCTION

James W. Hodges, Beaumont, Tex., assignor to Sun Oil Company, Philadelphia, Pa., a corporation of New Jersey

Original application December 20, 1949, Serial No. 134,011, now Patent No. 2,652,120, dated September 15, 1953. Divided and this application April 8, 1952, Serial No. 281,153

1 Claim. (Cl. 166—44)

1 This invention relates to a device adapted to be lowered into an oil well casing before the tubing is set in order to remove deposits from the well which would tend to prevent the free flow of fluid into or out of a well after the tubing has been set. In particular the device is designed to effect a series of steps in cleaning out the zone of contamination which normally exists between the sand face of an oil formation and the lower end of the casing which is in communication with the oil formation.

In the usual method for completing or preparing for production, oil, gas and salt water disposal wells, the well is of course first drilled through to the desired formation. For example, in preparing an oil well for production, the well would first be drilled to the oil formation and preferably 30 or 40 feet below the formation, in order that tools can be utilized in completing the well. After the well is drilled and the casing is positioned therewithin, the casing is set usually by cementing adjacent the sand face of the oil formation. Following this, in order to provide communication with the oil formation, the casing is perforated by what is normally known as gun-perforation in order to provide communication with the oil formation. In drilling the well, it is necessary to circulate a drilling mud into and out of the well as it is being drilled in order to remove the drilled out material. After the casing has been set and perforated, it is necessary to remove any drilling mud remaining in the well which is usually done by circulating water, and then a tubing string, which is of smaller diameter than the diameter of the casing, is inserted in the casing and maintained in fixed position within the casing by using what is known as a pack-off or packer which is positioned above the perforations in the casing; while the upper end of the tubing will be maintained in fixed position relative to the casing by a collar positioned around the tubing.

In the zone adjacent the perforated area of the casing other contaminants, in addition to drilling mud, are found which tend to prevent the free flow of fluid into or out of the well tubing, such as loose cement which has been deposited during the cementing operation, silt, and so forth. Various methods have been resorted to in order to remove these contaminants, but apparently no very satisfactory method has heretofore been devised since it often happens that after the well has been completed it may produce for a short time and then the perforations become plugged and flow into and out of the formation is no longer possible. Methods used heretofore to re-

move the contaminants are to wash them out of the well or to bail the contaminants from the well, but these methods have not been entirely effective and are time consuming.

The present invention is directed particularly to the idea of cleaning out the zone of contamination between the sand face of an oil or gas formation and the lower end of the casing, and additionally to remove any contaminants deposited on the casing wall; and the operations are carried out while the rig is in place and before completion equipment is installed within the casing, for example, before the tubing, packer, etc., are positioned within the casing. The invention practically assures that the well will start producing and continue to produce since substantially no contaminants will remain in the zone adjacent the perforations in the casing or on the casing wall.

Referring to the drawings:

Figure 1 is a vertical sectional view of the device with its various elements in their first position of operation within the well casing.

Figure 2 is a sectional view of the device with its various elements in their intermediate position of operation within the well casing.

Figure 3 is a vertical sectional view of the device with its various elements in the final position of operation within the well casing.

Since all of the figures are similar, each will have the various parts indicated by the same numerals and reference may be had to all of the drawings simultaneously.

Referring to the figures, 10 indicates the well which has been drilled, while 11 indicates the casing inserted into the well having perforations 12 therein to provide communication with the producing formation which, for the purpose of explaining the invention, will be considered an oil formation indicated at 13. The tubing string 14 is shown as having attached thereto a hollow tubular member 15, comprising one element of the cleaning device, having at its lower end a bit or drill 16, and located immediately above the bit is an apertured area made up of a plurality of ports 17. A tubular housing or sleeve 18 is positioned about the tubular member 15 providing a space 19 therewith, and adjacent its upper end the housing is provided with a plurality of friction springs 20 which contact the casing 11 and function to guide the device into the casing. The sleeve 18 at its lower end is provided with a resilient valve seat 21 which is apertured to permit the elongate member 15 to reciprocate therethrough. The member 15 is in effect a valve

rod since when it is pulled upwardly, the bit 16 will function as a valve plug to close the opening in valve seat 21. Directly below the valve ring or seat 21 is provided an inverted cup shaped member 22 which functions as a scraping element to remove, as the device is moved into the casing, any matter accumulated on the casing wall. Directly above the valve seat 21 is provided an apertured area which is enclosed by an inflatable seal ring 23 having an enlarged groove 24 therein. Directly above the seal ring 23 are provided ports or apertures 25 through which pressure is applied to inflate the seal ring 23 to effect a seal with the casing 10 as shown in Figures 2 and 3. The sleeve 18 at its upper end is provided with an inwardly extending flange 26 which cooperates with the joint 27 connecting the tubing 14 and inner tubular member or valve rod 15 to force the device into the casing.

Referring to Figures 1, 2, and 3, respectively, for the operation of the device, it will be seen in Figure 1 that the device has been lowered into the casing to locate the bit 16 at a point adjacent the casing perforations 12 and that the seal ring 23 at this time is not inflated, permitting free movement of the device into the casing and the device is guided during movement by the friction springs 20. The inverted cup shaped member 22 has moved to a line just above the perforations and its movement into the casing has scraped any accumulated matter from the casing wall in order to prevent injury to the packing or sealing ring 23.

In Figure 2, the inner tubular member 15 has been raised upwardly to position the bit 16 flush with the bottom of the valve ring 21 and also to position the apertures 17 adjacent the groove 24 in the ring 23. After the bit 16 has closed the aperture in the valve ring 21, water pressure is applied to the tubing string 14 and the liquid passes out of the inner member 15 through the apertures 17 to exert pressure through the groove 24 on the seal ring 23 to in effect inflate the ring and thereby provide a seal with the casing 11. Since the valve member 21 is flexible, the pressure of the water in the tubing will also be effective to cause a more firm contact with it and the drill 16, and hence assure at this time no leakage of the water into the casing. After the sealing ring has been expanded, the outer sleeve 18 is moved upwardly forcing the sealing ring 23 upwardly to cause a suction effect and draw through the apertures 12 into the casing material from the sand face adjacent thereto. Although not shown in the drawings, it will be understood that the lower end of the casing is closed and that suction will be effected on movement upwardly of seal ring 23. The effect of raising the device is to remove all of the hydrostatic head which had existed against the sand face of the formation by virtue of the salt water or mud in the well. This creates a pressure differential which causes the formation to produce momentarily into the casing, bringing with the formation fluid any sand, cracked cement, mud, silt, and other accumulations, small enough to pass through apertures 12, which might be present in the formation adjacent the sand face.

Referring to Figure 3, the pump pressure on the inner tubular member 15 has been released and the bit 16 lowered into the accumulated matter which had been pulled into the casing. Then the pumping connections at the surface of the well are manifolded to both the annulus and tubing so that liquid can be admitted to the annulus for passage through the ports 25 into the outer sleeve or housing 18 and through the valve ring or seat 21 into the casing below the seal ring 23. The liquid then will intermix with the contaminants or any loose material which has been pulled into the lower end of the casing 11, and enter the inner member 15 through the apertures 17 and pass to the surface through the tubing. The liquid pressure from the annulus between sleeve 18 and casing 11 passing through outer sleeve 18 will maintain the seal ring expanded and cause the liquid mixture to be forced upwardly from the lower end of the casing through the apertures 17 and out of the inner tubular member 15 and well tubing 14. In order to effect an agitation of the contaminants drawn into the casing the bit 16 can be rotated or reciprocated so that the contaminants in the lower end of the casing may more readily become intermixed with the circulated water. From the condition of the mixture of the water and contaminants, it can be determined when the accumulated matter drawn into the casing has been removed and the operation can be repeated until it appears that no contaminants are being pulled into the casing from the well formation.

This application is a division of my copending application, Serial No. 134,011, filed December 20, 1949, now Patent No. 2,652,120.

I claim:

Method of preparing a well for production, after the well casing has been installed and is provided with a perforated area in its lower portion for communicating with the producing formation, which comprises the steps of scraping accumulated matter from the casing between its top and bottom and depositing it in the lower portion of the casing adjacent the perforated area, sealing the lower portion of the casing from the upper portion, applying suction to the lower portion of the casing in order to draw through the perforated area loose material from the producing formation, releasing suction and directing a stream of liquid downwardly, through one passageway, into the lower portion of the casing to intermix with material accumulated therein and thence upwardly through a second passageway to a discharge to thereby effect removal with the stream of liquid of said accumulated matter.
